UNITED STATES PATENT OFFICE.

LEE W. HARPHAM, OF SAN FRANCISCO, CALIFORNIA.

GAME-BAG.

No. 797,279.

Specification of Letters Patent.

Patented Aug. 15, 1905.

Application filed May 10, 1905. Serial No. 259,820.

To all whom it may concern:

Be it known that I, LEE W. HARPHAM, a citizen of the United States, residing in the city and county of San Francisco and State of California, have invented new and useful Improvements in Game-Bags, of which the following is a specification.

The object of my invention is to provide a bag in which a considerable quantity of wild game may be carried, which may be thrown over the shoulder of the hunter, and which will protect the clothing of the hunter from being soiled by the game and will also protect the game from coming in contact with anything outside the bag whether the same is being carried by the hunter or whether the bag is on the ground or elsewhere off the hunter, thereby keeping the game in a smooth neat condition while it is being carried on and from the hunting-preserve; also, to provide a bag which is thoroughly ventilated, so as to keep the game in as good condition as possible during the time it is in the bag. I accomplish these objects by the game-bag described herein and illustrated in the accompanying drawings, in which—

Figure 1 is a plan of my game-bag, partly broken away to show details of construction. Fig. 2 is a section on the line 2 2 of Fig. 1 with the bag in the position that it would assume if it were thrown over the shoulder. Fig. 3 is a plan of the game-strap to which the game is secured and held in the bag.

At each end of the game-strap 5 are the game-loops 6, into which the head of the game is usually thrust to hold it upon the strap. There may be as many of these loops on each end of the strap as desired. To the center of the game-strap is secured a retaining-loop 7 for the passage therethrough of the holding-strap 8, which strap is secured at the ends to the center 9 of the bag. The holding-strap is provided with a buckle 10 or other convenient fastening means to permit the game-strap to be removed from the bag. Toward the ends the casing of the bag widens out and then contracts inwardly and forms the holding-receptacles 11 and 12, which inclose and surround the game on the ends of the game-strap. The upper side of the casing of the bag is provided with an opening which extends from nearly one end to the other, and the parts overlap at this opening, and after the game is secured to the game-strap in the bag these parts are removably secured together by any fastening device. I have shown

on the right-hand side of Fig. 1 a strap 13 secured to one side of the casing and a buckle 14 secured to the other side of the casing. On the left-hand side of Fig. 1 the parts are held removably secured together by hooks 15, secured to one part, and eyes 16, secured to the other part. The casing may be provided with a plurality of eyelets 17, so as to ventilate the interior of the bag when there is game in it.

If desired, the game-strap could be permanently secured to the casing by sewing or riveting it in the center instead of by the removable means described and shown herein; but it would not be as convenient, and for that reason I prefer the method of removably attaching the game-strap to the protecting-bag. By securing the game-strap removably to the protecting-bag the hunter when he leaves the field can take the game out of the bag and nicely arrange it for transportation and then put it back in the protecting-bag and secure the fastenings, so as to securely protect the game from injury or disarrangement while it is being transported. The protecting-bag is preferably made of canvas, but, if desired, could be made of oil-cloth or other material.

Having described my invention, what I claim as new, and desire to secure by Letters Patent, is—

1. A game-bag composed of two holding-receptacles united together and having the top portion provided with a slit therein on the upper side thereof; means to removably secure the parts forming the slit together; and a game-strap secured thereto, loops on the end thereof, said loops projecting into the holding-receptacles.

2. A game-bag composed of two pear-shaped holding-receptacles united together and having the top portion of each holding-receptacle provided with an opening or slit therein and having means to secure the parts forming the sides of the slit together; a game-strap having game-loops at each end thereof; a retaining-loop secured to the center of said game-strap; a holding-strap secured to the portion of the bag uniting the receptacles, said holding-strap being adapted to pass through the retaining-loop on the game-strap and to have the parts thereof removably fastened together.

3. A game-bag composed of two pear-shaped holding-receptacles united together and having a plurality of ventilating-apertures in said holding-receptacles and a slit

extending from near the outer end of one receptacle to near the outer end of the other receptacle on the upper side thereof; means to secure the parts forming the sides of the slit together; a game-strap having retaining-loops on the ends thereof in said bag; and means to removably secure said game-strap in said bag.

In witness that I claim the foregoing I have hereunto subscribed my name this 22d day of April, 1905.

LEE W. HARPHAM.
